United States Patent Office

Des. 193,188
Patented July 10, 1962

193,188

VASE

Orville C. Hamon, Cedars, Okla.
(% Scott Glass Co., P.O. Box 813, Fort Smith, Ark.)

Filed Nov. 24, 1961, Ser. No. 67,691

Term of patent 14 years

(Cl. D29—28)

FIGURE 1 is an end elevational view of a vase according to my new design;

I claim:

The ornamental design for a vase, as shown.
